UNITED STATES PATENT OFFICE.

CHARLES A. WALKER, OF PITTSBURG, KANSAS.

GAGE-COCK.

1,113,267.

Specification of Letters Patent.

Patented Oct. 13, 1914.

Application filed August 28, 1913. Serial No. 787,188.

To all whom it may concern:

Be it known that I, CHARLES A. WALKER, a citizen of the United States, residing at Pittsburg, in the county of Crawford and 5 State of Kansas, have invented a new and useful Gage-Cock, of which the following is a specification.

The present invention appertains generally to gage cocks, and aims to provide a 10 novel and improved device of that character.

One of the objects of the present invention is to provide a gage cock applicable to boilers and the like, and embodying a valve adapted to be seated outwardly by the steam 15 or water pressure.

Another object of the present invention is to provide a device of the nature indicated embodying a barrel adapted to be engaged through the boiler shell, and a valve stem 20 passing through the barrel and provided at its inner end with a valve seatable against the inner end of the barrel, to close the passage through the barrel, the outer end of the stem being adapted to be manipulated or slid 25 inwardly to open the valve.

A still further object of the present invention is to provide novel means for actuating or manipulating the valve.

The present invention also has for its object 30 to provide novel means for cleaning or clearing the interior of the valve of any scale or extraneous matter which may have accumulated or collected therein.

The invention also contemplates the provision 35 of a simple and efficient appliance of the character specified, which shall possess superior advantages as over existing devices of this character, and which shall be characterized by unique features to render the 40 present device more desirable and effective.

With the foregoing general objects outlined, and with other objects in view, which will be apparent as the nature of the invention is better understood, the present invention 45 resides in the combination and arrangement of parts and in the details of construction hereinafter described and claimed, it being understood that changes in the precise embodiment of the invention herein dis- 50 closed, can be made within the scope of what is claimed, without departing from the spirit of the invention.

The invention has been illustrated in its preferred embodiment in the accompanying 55 drawing, wherein:

Figure 1 is a longitudinal central section

of the device, parts being shown in full. Fig. 2 is a plan view. Fig. 3 is a front end view of the device. Fig. 4 is an enlarged sectional detail taken on the line A—B of 60 Fig. 1.

In carrying out the invention, reference being had in detail to the drawing, there is provided a barrel or tubular body 1 which may be cast or otherwise fashioned from suitable metal. The barrel 1 is provided with a longitudinal circular bore 2, the forward or outer end of which is contracted, as at 3. The bore 2 is enlarged adjoining the forward or outer end of the barrel 1, or 65 adjoining the contracted portion 3, to provide the chamber 4. The barrel 1 is provided with a depending nipple or nozzle 5 adjoining its forward end, the duct 6 of the nipple communicating with the chamber 4. 70 The rear end of the barrel 1 is provided with a tapered thread 7 for convenience in engaging the said end of the barrel through the shell of a boiler, or other object. The inner end of the barrel is also provided with 75 an internal bevel, or is countersunk, to provide a valve seat 8 at the inner or rear end of the bore. A stem 9 extends through the bore 2, the forward or outer end of the stem being contracted, as at 10, and passing 80 through the contracted portion 3 of the bore, so as to protrude beyond the forward end of the barrel. The inner or rear end of the stem 9 is provided with a head 11 forming a valve, the shoulder 12 of the head or valve 90 being conical so as to seat within or against the seat 8 of the barrel, and the valve 11 being provided with the conical or pointed extension 13. The stem 9 has three of its sides flattened, as at 14, from the valve or head 11 95 to a point short of the reduced portion 10, the flattened portions 14 forming passages 100 leading from the chamber 4 to the rear or inner end of the barrel. The stem 9 may thus be said to have longitudinal passages 100 extending from the chamber to the valve, it being observed that the stem 9 is disposed snugly within the bore of the barrel.

A packing or socket nut 15 is threaded over the forward or outer end of the barrel, 105 suitable packing 16 being disposed within the nut 15 to be compressed against the reduced or forward end portion 10 of the stem, to preclude leakage.

A hand wheel 17 is secured upon the forward or outer end of the stem, or on the reduced portion 10, the hub 18 of the handle

being secured tightly upon the stem, and extending inwardly or rearwardly from the rim of the hand wheel. A jam or set nut 19 is preferably threaded onto the extremity 5 of the stem to bind the hub 18 of the hand wheel in position. A coiled wire spring 20 encompasses the valve stem and is compressibly disposed between the packing nut 15 and the inner end of the hub 18, so as to 10 yieldingly force the stem and its valve outwardly, to seat the valve. The hub 18 is provided with an exterior flange 21 adjoining its inner end, for the purpose which will hereinafter appear.

15 A vertical or depending actuating lever 22 arranged at right angles to the axis of the body or barrel is provided for opening the valve, the same being provided with a straight fork 23 at its upper end and having 20 a handle 24 at its lower end; the fork 23 straddling the hub 18 intermediate the rim of the hand wheel and the flange 21. A link 25 connects the upper end of the lever 22 and the back of the barrel 1, the forward 25 end of the link 25 being pivoted between the ends of the arms of the fork 23 by means of a bolt or pivot pin 26, and the inner end of the link being pivoted between a pair of upstanding ears 27 formed on the back of 30 the barrel. The link 25 is pivoted between the ears 27 by means of a bolt or pivot pin 28. A cross pin 29 is terminally riveted or secured through the arms of the fork 23, and rests upon the hub 18 directly in advance 35 of the annular or circumferential flange 21 formed on the hub.

The use of the present device is accompanied by the following advantages: When the barrel 1 is engaged to the shell of a boiler, 40 it will be observed that the valve will be disposed upon the interior of the boiler, and in seating against the inner end of the barrel will normally prevent scale collecting upon the interior of the barrel. The steam 45 or water pressure will also assist in seating the valve, and perchance, should the spring 20 be broken or removed, or should the valve stem become broken, the steam or water pressure alone would serve to seat the valve, 50 in order to prevent the escape of the steam and water, which would result in a "dead" boiler. If under any condition, the scale or lime should creep into the barrel, due to leakage between the valve and its seat, the 55 scale or extraneous matter may be readily cleared from the barrel, by rotating the valve stem through the medium of the hand wheel 17, whereby the edges of the valve stem will shear or grind the scale from the 60 interior walls of the bore 2. Then, by opening the valve, the foreign matter may be blown off. It is to be noted in this connection that the valve stem is approximately triangular in cross section, that is, at its 65 rear end portion, between the chamber 4

and the valve, so as to provide longitudinal cutting or shearing edges extending from the valve and coöperating with the walls of the bore leading from the valve seat for the purpose just described. The hand wheel 17 70 also permits the stem to be rotated for regrinding the valve and its seat, as will be apparent. The broken scale may readily be discharged by first passing into the chamber 4 and then through the nipple 5 75 with the water or steam. To manually open the valve, the handle 24 of the lever 22 is grasped, and forced inwardly, or toward the boiler, which will press the valve stem inwardly to unseat the valve, whereby the 80 water or steam may flow through the bore 2 to the chamber 4, and thence out the nipple or nozzle 5. When the lever is released, the valve will seat automatically, through the tension of the spring 20, assisted by the 85 steam or water pressure. As above intimated, the valve will seat of itself without the assistance of the spring, the spring expediting the seating of the valve. It will be observed that when the hand wheel is 90 turned, the pin 29 will continually coöperate with the flange 21, so that the valve stem may be forced inwardly irrespective of the particular position of the valve stem about its axis, the fork 23 also engaging the flange 95 21 and the crotch of the fork receiving the hub 18.

Another feature of the present invention, resides in the fact that a shoulder is provided by the reduced portion 10 of the stem, 100 which coöperates with the shoulder formed by the portion 3 of the bore, whereby should the valve stem be broken in rear of the said shoulders, the outer portion of the valve stem will be prevented from being ejected 105 by the spring, or by the water or steam pressure.

From the foregoing, taken in connection with the drawing, the advantages and capabilities of the present invention will be apparent, the present device being adapted primarily for use on locomotive or stationary boilers, but being applicable for other purposes as well.

Having thus described the invention, what 115 is claimed as new is:—

In a device of the character described, a body having a valve seat and bore leading therefrom, a stem slidable through the bore, and having a valve coöperating with the 120 said seat and longitudinal shear edges extending from the valve and coöperating with the walls of the bore, a hand wheel having a hub secured on the outer end of the stem, the hub being extended inwardly 125 and having an exterior flange at its inner end, a lever disposed at right angles to the axis of the body and having a straight fork straddling the hub between the hand wheel proper and the flange, a link having one end 130

pivoted between the ends of the fork arms, and having its other end connected to the body, a pin engaged through the arms of the fork, the said hub being disposed snugly
5 between the said pin and the crotch of the fork, and a coiled wire spring upon the said stem between the body and hub.

In testimony that I claim the foregoing as my own, I have hereto affixed my signature in the presence of two witnesses.

CHAS. A. WALKER.
